UNITED STATES PATENT OFFICE.

WILLIAM B. MACK, OF BOSTON, MASSACHUSETTS.

LOCOMOTIVE-BOILER.

SPECIFICATION forming part of Letters Patent No. 506,054, dated October 3, 1893.

Application filed February 1, 1893. Serial No. 460,603. (No model.)

To all whom it may concern:

Be it known that I, WILLIAM B. MACK, of East Boston, in the county of Suffolk and State of Massachusetts, have invented certain new and useful Improvements in Locomotive-Boilers, of which the following is a specification.

This invention relates to that class of locomotive boilers in which provision is made for the rapid circulation of water from the lower forward portion of the boiler to the lower portion of the water-leg, for the purpose of insuring the passage of the maximum quantity of water through the water-leg, and therefore the maximum rapidity of heating and steam generating.

In Letters Patent No. 487,535, granted to me December 6, 1892, I have shown means for providing for the passage of water from the forward portion of the boiler directly to the lower portion of the front side of the water-leg, said means comprising a conduit adapted to conduct water between the two points specified, portions of said conduit being applied to the exterior of the boiler and water-leg, so that the construction involves not only the formation of orifices in the external shell of the boiler and in the exterior wall of the water-leg, but also external connecting devices or parts.

My present invention has for its object to simplify and reduce the cost of the means employed for producing the desired result, and to enable said result to be produced without the employment of any external additional parts, and without the formation of orifices in the shell of the boiler or in the external wall of the water-leg.

To these ends, the invention consists in the combination with a locomotive boiler and its water-leg of a sectional conduit formed to extend along the bottom of the boiler from the forward end thereof to the front wall of the water-leg, and pipes detachably secured to the rear end of said conduit and extending downwardly to a point near the bottom of the front portion of the water-leg, two of said pipes being arranged so that their lower ends will be in position to deliver the water that passes through them into the side portion of the water-leg, while another pipe (there may be one or more) delivers water at the lower

portion of the front wall of the water-leg, at or near the center thereof, said conduit and pipes being located wholly within the boiler 55 and water leg and adapted to be applied to the boiler without making any structural change in the boiler or water-leg, all of which I will now proceed to describe.

Of the accompanying drawings, forming 60 part of this specification, Figure 1 represents a longitudinal section of a portion of a locomotive boiler provided with my improvement. Fig. 2 represents a section on line 2—2, Fig. 1, looking toward the right. Fig. 3 represents a perspective view of the conduit and pipes.

The same letters of reference indicate the same parts in all the figures.

In the drawings: *a* represents a locomotive 70 boiler, having the usual water-leg *b*, communicating with the rear portion of the boiler as usual.

In carrying out my invention, I place at the bottom of the boiler a conduit *c* composed of 75 two or more sections detachably connected by means of bolts *c'* passing through ears *c''* on the sections. Said conduit extends from the front lower portion of the boiler backwardly to the front wall of the water-leg, and 80 is open at its front end and closed at its rear end, so that they extend down nearly to the bottom of the water-leg, each pipe being open at both ends, and constituting a conduit adapted to conduct water from the forward 85 lower portion of the boiler to the top of the front portion of the water-leg.

To the rear portion of the sectional conduit *c* are detachably secured pipes *d d' d'* which extend downwardly to points near the bottom 90 of the front part of the water-leg and constitute outlets from the conduit, the pipes *d d'* being extended outwardly in opposite directions from the conduit as shown in Figs. 2 and 3, so that the streams of water delivered 95 by said pipes into the water-leg will pass directly into the side portions of the water-leg, thus insuring a suitable supply of water for said side portions, and preventing the liability of steam being formed therein, to the detriment of the inner walls of the water-leg. The intermediate pipe *d* is carried downwardly to the lower portion of the water-leg, and delivers water at or near the center of

the front wall of the water-leg. There may be more than one of the intermediate pipes *d* if desired.

It will be seen that the sectional conduit *c* and the pipes *d d' d'* may be applied to the boiler and water-leg of a locomotive of ordinary construction, without making any change in the construction of the boiler and water-leg, so that my improvement enables old boilers to be readily fitted with means for increasing the rapidity of the circulation of water, the sectional construction of the conduit enabling it to be readily inserted in an old boiler by assembling and connecting the sections within the boiler, while the detachable connection of the pipes to the conduit enables the pipes to be set in place after the conduit has been applied. The pipes may be detachably secured to the conduit by means of screws or bolts passing through flanges formed on the pipes or by any other suitable means.

I claim—

1. The combination with a locomotive boiler and its water-leg, of a conduit extending lon-

gitudinally of the boiler along the bottom of the same from the forward portion to the front portion of the water-leg, and pipes connected with the rear of said conduit and extended to the lower portion of the water-leg, two of said pipes being arranged to deliver water at points coinciding with the side portion of the water-leg, said conduit and pipes being located wholly within the boiler and water-leg, as set forth. 30

2. The improved attachment for locomotive boilers, the same comprising in its construction the conduit *c* composed of detachably connected sections and the pipes *d d' d'* detachably secured to one end of said conduit and extending at an angle therewith, as set forth. 35

In testimony whereof I have signed my name to this specification, in the presence of two subscribing witnesses, this 20th day of January, A. D. 1893. 40

WILLIAM B. MACK.
